LIQUID FUEL VAPORIZER

Charles A. French, Riverside, Ill.

Application June 15, 1933, Serial No. 675,933

8 Claims. (Cl. 158—53)

This invention relates to a fuel vaporizer. More particularly it relates to a vaporizer construction particularly designed for handling heavy liquid hydro-carbons.

5 The principal object of the invention is to provide a vaporizer which will completely vaporize heavy liquid fuels and maintain them in vaporized condition when mixed with air sufficient for complete blue flame combustion.

10 Another object is to provide an improved construction for vaporizing liquid fuels by complete combustion of a portion of the fuel in direct contact with the remainder of the fuel.

These objects and others which will be apparent 15 from the description to follow, are accomplished by a particular construction as shown in the single figure of the drawing which illustrates a vertical section of the device.

A casing 10, which forms the vaporizing chamber, is in the form of a flat drum positioned horizontally, the side wall being a cylinder short in height compared to diameter and the bottom and top walls being circular. A plurality of rows of openings 11 are provided around the cylindrical wall of the casing. A perforated cylindrical member 12, which may be perforated as shown or formed as a screen, is mounted within the casing 10, spaced from the cylindrical wall thereof and extending to the top and bottom 20 walls. A conical baffle member 13 is mounted within the casing concentric with respect thereto, the small end of the cone being adjacent the top of the casing. A plurality of openings 14 are formed around the bottom of the conical baffle member. A cylindrical member 15 extends from below the bottom wall of the casing, through said bottom wall, and into contact with the conical baffle member 13. Said cylindrical member is perforated between the conical baffle member and 25 the bottom wall of the casing.

A fan or blower housing 16 is positioned below the casing 10, spaced therefrom, and held in position by a flanged cylindrical spacing member 17 secured to the housing and to the bottom of the 30 casing. A shaft 18 extends vertically through the bottom of the housing and centrally through the member 15 and the conical member 13, into the main chamber of the casing 10. Suitable bearings are formed on the bottom wall of the housing 35 and in the baffle member 13 for said shaft. The flanged discharge of the fan housing may be connected directly to the supply chamber of a burner grating or with a conduit leading to a more distant location.

40 At the upper end of the shaft adjacent the top

of the casing 10, a distributor disk 19 is mounted for rotation with the shaft. A nozzle 20 extending into the top of the casing, centrally thereof, is connected with a conduit 21 for supplying liquid under pressure to the nozzle. A spark plug 22 is 45 mounted in the top wall of the casing 10.

An impeller or fan 23 is mounted on the shaft 18 within the housing 16. It will be noted that the cylindrical member 15 extends down to and slightly within the upper horizontal wall of the 50 housing 16 adjacent the inner ends of the blades forming the impeller. An opening 24, formed in the upper wall of the housing 16, provides an annular space for the admission of air around the cylindrical member 15. A plurality of openings 25 formed in the connecting member 17 provide for the admission of air therethrough for delivery to the blower. A pulley 26 is mounted on the shaft 18 for the application of power thereto.

In the operation of the vaporizer, as above 55 described, liquid fuel is fed through the nozzle 20 on to the disk 19, which is driven at a comparatively high rate of rotation. The fuel is distributed from the periphery of said disk as a spray, upon the screen 12. By means of the 60 spark plug 22 said spray is ignited. At the initiation of the vaporizer a limited amount of liquid is delivered on the disk 19, whereby sufficient air is 65 available by entrance through the openings 11 and the screen 12, to maintain substantially complete combustion whereby the vaporizer parts are 70 quickly warmed up so that the vaporizer can then be put into full operation. The fan 23 draws air through the annular inlet formed by the opening 24 and gases through the cylindrical member 75 15 from the vaporizer. The parts are so proportioned that with full operation sufficient air is 80 drawn in and mixed with the vaporization products for complete combustion thereof.

As greater quantities of fuel are delivered to 85 the disk 19 the vaporization products are formed in amounts greater than the air available for complete combustion. The flame of combustion is then confined to the small jets of air coming 90 through the screen 12, burning in the atmosphere of atomized and vaporized fuel. The heat thereby generated is sufficient to vaporize the entire amount of fuel being distributed and to superheat the vaporization products to such an extent 95 that they will not condense during passage 100 through the remainder of the apparatus and during mixing with the air in the housing 16 for complete combustion. The liquid fuel being sprayed from the disk 19 flows down the inner side of the screen 12 and tends to bridge over 105 110

5 by capillary action the small openings formed therein. The small amount of air being admitted forms jets through these openings, burning the fuel in the vicinity thereof and permitting there-
6 by sufficient heat for the vaporization of the re-
mainder of the fuel.

It is to be understood that applicant has shown
and described only a preferred embodiment of his
improved fuel vaporizer and that he claims as his
10 invention all modifications falling within the scope
of the appended claims.

What is claimed is:

1. A liquid fuel vaporizer comprising a vapor-
15 izer casing, a screen mounted within said casing
spaced from the walls thereof, restricted means
to admit air in limited amounts through the cas-
ing to said screen, means for distributing liquid
fuel in finely divided form in the casing, means
20 to ignite said fuel, means to withdraw the re-
sultant combustion and vaporization products
from the casing, and means to mix said products
with air sufficient for complete combustion.
2. A vaporizer comprising a vaporizer casing,
25 a screen mounted within said casing spaced from
the walls thereof, restricted means to admit air
in limited amounts through the casing to said
screen, means for distributing liquid fuel in finely
divided form in the casing and on said screen,
30 means to ignite said fuel, means to withdraw the
resultant combustion and vaporization products
from the casing, and means to mix said products
with air sufficient for complete combustion.
3. A liquid fuel vaporizer comprising a vapor-
35 izer casing, a screen mounted within said cas-
ing spaced from the wall thereof, restricted means
to admit air in limited amounts through the cas-
ing to said screen, means for distributing liquid
fuel in finely divided form in the casing, means
40 to ignite said fuel, means to withdraw the re-
sultant combustion and vaporization products
from the casing, a blower housing secured to the
vaporizer casing, means for delivering gases from
the casing to said housing, and means for de-
45 livering air to the housing.
4. A liquid fuel vaporizer comprising a vaporizer
casing, a cylindrical screen mounted within said
casing spaced from the wall thereof, restricted
means to admit air in limited amounts through
50 the casing to said screen, a rotating disk mounted
within the casing, means for delivering fuel to
said disk, means to ignite said fuel, means to
withdraw the resultant combustion and vaporiza-
tion products from the casing, and means to mix
55 said products with air sufficient for complete
combustion.
5. In a vaporizer and burner a cylindrical
vaporizing casing, inlet openings around the
cylindrical wall of the casing, a cylindrical screen
60 within the casing extending from top to bottom
thereof and spaced from the wall of the casing,
a baffle member in the casing mounted concentric
with respect thereto, openings in the baffle mem-
ber forming communication between the main
65 portion of the casing and the portion beneath
the baffle member, a cylindrical member extending
through the bottom wall of the casing into contact
with the baffle member, the portion of said mem-
ber within the casing being perforated to form
70 means of communication between the interior of
the member and the portion of the casing be-
neath the baffle member, a blower housing pro-
vided with a central inlet opening, means for
mounting said housing in spaced relation with
75
6. In a vaporizer and burner a cylindrical
vaporizing casing, inlet openings around the
cylindrical wall of the casing, a cylindrical screen
within the casing extending from top to bottom
thereof and spaced from the wall of the casing,
80 a baffle member in the casing mounted concentric
with respect thereto, openings in the baffle mem-
ber forming communication between the main
portion of the casing and the portion beneath the
baffle member, a cylindrical member extending
85 through the bottom wall of the casing into contact
with the baffle member, the portion of said mem-
ber within the casing being perforated to form
means of communication between the interior of
the member and the portion of the casing be-
90
7. In a vaporizer and burner a vaporizing cas-
ing cylindrical in shape, inlet openings around
the cylindrical wall of the casing, a cylindrical
screen within the casing extending from top to
bottom thereof and spaced from the cylindrical
95 wall and casing, a conical baffle member in the
casing mounted concentric with respect thereto,
openings in the baffle member forming communica-
tion between the main portion of the casing
and the portion beneath the baffle member, a
100 blower housing, means for mounting said housing
in spaced relation with respect to the vaporizing
casing, the cylindrical member from the bottom
wall of the casing extending adjacent the central
inlet opening of the blower housing, a blower fan
105 mounted within the housing, a rotatable fuel dis-
tributing disk mounted in the vaporizing casing,
means for supplying fuel to said disk, and means
for igniting fuel spray delivered from said disk.
8. In a vaporizer and burner a vaporizing cas-
ing cylindrical in shape, inlet openings around
the cylindrical wall of the casing, a cylindrical
110 screen within the casing extending from top to
bottom thereof and spaced from the cylindrical
wall and casing, a conical baffle member in the
casing mounted concentric with respect thereto,
openings in the baffle member forming communica-
115 tion between the main portion of the casing
and the portion beneath the baffle member, a
blower housing, means for mounting said housing
in spaced relation with respect to the vaporizing
casing, means for connecting the portion of the
120 vaporizer casing beneath the baffle with the blower
housing, a blower fan mounted within the hous-
ing, a fuel distributing means mounted within the
vaporizing casing, means for supplying fuel
thereto, and means for igniting fuel spray deliv-
125 ered from said distributing means.
9. In a vaporizer and burner a vaporizing cas-
ing cylindrical in shape, inlet openings around
the cylindrical wall of the casing, a cylindrical
130 screen within the casing extending from top to
bottom thereof and spaced from the cylindrical
wall and casing, a conical baffle member in the
casing mounted concentric with respect thereto,
openings in the baffle member forming communica-
135 tion between the main portion of the casing
and the portion beneath the baffle member, a fuel
distributing means mounted within the vaporizing
casing, means for supplying fuel thereto, and
means for igniting fuel spray delivered from said
140 distributing means.
